UNITED STATES PATENT OFFICE.

OTTO P. WERNER, OF MILWAUKEE, WISCONSIN, ASSIGNOR, BY MESNE ASSIGNMENTS,
TO KAUMAGRAPH CO., OF NEW YORK, N. Y., A CORPORATION OF NEW YORK.

APPARATUS FOR LABELING GOODS SUCH AS STOCKINGS AND THE LIKE.

Application filed September 11, 1925. Serial No. 55,734.

This invention relates to improvements in apparatus for labeling goods such as stockings and the like, and pertains more particularly to an arrangement and combination of devices whereby such work may be carried on more conveniently and expeditiously.

Stockings are usually stamped on the toe with a mark of identification or label together with the size number and whatever else is desired. These labels are applied by the so-called transfer process, that is, the labels are printed in colored wax, or a substance of low melting point, on a roll of paper. The paper with the label down is placed over the goods in the desired place and a hot iron is then pressed down over the paper, causing the label to be transferred to the surface of the goods.

Among the objects of the invention are to provide apparatus whereby the operator is enabled to perform the stamping and labeling operations at a higher rate of speed than has been possible heretofore, in a more perfect and accurate manner, with less likelihood of making errors, with less fatigue, and with fewer and shorter motions. Other objects and advantages will become apparent from the following description taken in connection with the accompanying drawings wherein one form of the invention is illustrated.

In the drawings:

Figure 1 is a front perspective view of a device embodying my invention;

Fig. 2 is a sectional elevation taken on line 2-2 of Fig. 1;

Fig. 3 is an elevation of the rack and frame parts with intermediate portions broken away.

Fig. 4 is an enlarged section on line 4-4 of Fig. 3;

Fig. 5 is an enlarged section on line 5-5 of Fig. 3; and

Fig. 6 is a fragmentary view of the lower corner of the guide roll rack.

Referring more in detail to the drawings, 7 designates a work table of suitable height and construction, its top 8 being provided with cut-out portions 9 and 9^a in the front and rear edges thereof. A slidable work support 10 is mounted on the table top 8 forwardly of the cut-away portion 9 and

comprises a plate 11 secured on a block 12 which is recessed as at 13 along its lower edges. Rollers 14 carried by block 12 and

positioned in the recesses thereof are adapted to engage in the grooves 15 of guide bars 16 which extend transversely of the table top 8 whereby the support 10 is slidable for a short distance to and from the operator 60 who occupies the position immediately in front of table 8 as defined by the cut-away portion 9.

A heating or stamping element shown in the drawings in the form of an iron 17 is 65 held above support 10 and is adapted to be swung down thereon. The iron 17 has a bail 18, the center of which is fastened to the bottom of the head block 19 which is mounted so that its axis remains vertical in 70 moving by means of a parallel link motion comprising an arm 20 and a guide bar 21 pivoted at equidistant points in head block 19 at one end and in the bracket 22 at the other, the bracket 22 being secured in any 75 suitable way to the table top 8. The arm 20 and bar 21 are each offset so that the bracket or stand 22 is at one side of the work support 10, thereby leaving the space behind the support and under the iron 17 80 free of obstructions.

The arm 20 has a rearwardly extending portion 23 pivotally fastened to the end of the link 24 which extends through a slot 25 in the table top 8 and is adjustably pivoted 85 to the knee of a foot lever 26 which swings from a bracket 27 secured to the underside of the table top 8. The foot lever 26 is so proportioned and balanced that it will normally assume a position to hold the sad iron 90 19 in raised or inoperative position, as shown in full lines in Fig. 2. To lower the iron onto the work, the operator pushes back on the lower end of the foot lever. Other means, of course, may be used to raise and 95 lower the iron.

An assortment of transfer rolls 28 are carried in a rack 35 which is slidably mounted in the frame 29. The rectangular angle-iron frame 29^a is secured in a vertical position in the rear cut-away portion 9^a of the table by means of brackets 30. Guide rails 32 and 33 are secured across the upper and lower ends of frame 29^a. A notched bar 34 is spaced rearwardly from and is secured to frame 29^a near the middle thereof. 100 105

The rack or roll frame 35 comprises a plurality of spaced pairs of bars 36 secured together at the top and bottom by means 110 115

of the tube-and-rod ties 37. The bars 33 are provided with a series of suitably spaced apart inclined notches 38 for receiving the pintles 39 of the roll cores 40.

5 The rack shown is adapted to hold a set-up of four different colored transfer rolls, one color being in each of the vertical tiers and arranged, for example, with a size 9 at the bottom, then 9½, 10, and so on up to 10 the top.

The rack 35 is supported by wheels 41 which ride on the top rail 32 and are secured to the rack by means of the sheave plates 42' which pass down on either side of the 15 rail 32 and are bolted to the top tie 37. The outer rack bars 36^a are extended at the upper and lower ends and notched to slidably engage with the rails 32 and 33 for holding the rack structure 35 in place.

20 A series of pairs of guide rolls 42 are mounted in a secondary frame 43 which is carried by the roll frame 35 and supported thereby above the table. A pair of guide rolls 42 is provided for each of the transfer 25 rolls 28, each upper roll 42 of each pair having a pin journaled in a slot 44' whereby it may be raised out of contact with the lower roll to facilitate insertion of the strip of transfer material between the rolls. 30 The end of each of the rolls of transfer paper is passed between the proper pair of guide rolls and is held in position by the pressure between the rolls caused by weight of the upper roll.

25 A swinging handle bar 44 is pivoted to the rack side bars 36^a, and has a rearwardly extending finger or latch 45 adapted to engage in the notches in the bar 34. The latch 45 is pulled downwardly by means of the spring 46 which is fastened to said latch and to frame 43, and thus serves to hold the frame 35 in a selected position.

40 A guide roll 47 is pivotally mounted in a bracket 48 secured to the table top 8 and is located directly behind the sliding support 10.

45 The device is used in substantially the following manner: The operator sits in position in front of the table with bundles of stockings sorted in colors and sizes stacked at one side. A bundle is placed with the toe portions in position on the top of the sliding support 10. The end of the roll bearing the proper labels and size number is drawn out from the holding rack 43, passed under the guide roller 47 and laid over the topmost stocking with the label correctly placed. The support 10 is then shifted forward or backward so that the iron 17 will strike directly over the label. The iron 17 is then brought down, held until the label has been transferred and then released. The operator then lays back the ends of the top pair of stockings, 50 draws a new label into place and repeats the

operation until the stack is exhausted. The bundle is then passed to the other side of the table, a new bundle put on the stand, the proper label roll selected and the operation repeated.

70 The labeling is rapidly performed with a very small number of different motions required by the operator, and the goods and the labels are very conveniently arranged for selection. The label is positioned on the goods and then the work support 10 is shifted so that the label comes under the iron without disarranging the position of the label. It will also be seen that the shiftable support 10 permits positioning of the pile of goods so that the uppermost stocking in the pile may be placed in proper position to be engaged by the iron.

75 It is obvious that the improvements are susceptible of various changes and modifications without departing from the spirit of the invention and it is not, therefore, desired to limit or restrict the same except where limitations appear in the appended 80 claims.

85 The invention claimed is:

1. In combination, a stamping element 90 mounted for movement in a vertical plane and normally held in a raised position, means for lowering and raising said element, a work support adapted to be positioned in the path of movement of said element, a fixed frame-support, a slideable frame mounted on said support and holding a plurality of transfer rolls arranged in vertical rows, said slideable frame adapted to be positioned so that any one of the transfer rolls may be operatively positioned relatively to said support.

100 2. In combination, a table, a stamping element movably mounted thereon, a work support mounted on said table in the path of said element, means for moving said element into and out of engagement with said support, a slideable rack adapted to hold a plurality of transfer rolls arranged in vertical rows, and means for positioning the rack with respect to the work support.

110 3. In combination, a pivotally mounted arm, a stamping element pivoted in the free end thereof, a guide bar pivoted at equidistant points from the pivot point of the arm and the pivot point of said element respectively and on the same side as said pivots, a pivotally mounted depending operating lever, and a link pivotally connecting the arm and the depending lever.

115 4. In combination, a rack, transfer rolls arranged in vertical rows thereon, a guide frame carried by the rack, guide rollers corresponding to said transfer rolls pivoted in the guide frame, the upper roll of each pair being slideable vertically with respect to the lower roll thereof.

120 5. In combination, a stamping element

- mounted for movement in a vertical plane and yieldingly held in a raised position, a work support mounted in operative relation with respect to said element and slid-
5 able normally to the path of motion of said element, a guide roll located to the rear of and in line with the support, a rack adapted to hold a plurality of transversely slidable transfer rolls arranged in vertical rows to
10 the rear of said guide roll, and means for releasably holding the rack in a desired position with respect to the said guide roll.
6. The combination as set forth in claim 5, further characterized by a guide roll
15 frame carried on the front of said rack, a plurality of pairs of guide rolls pivoted in the guide roll frame and corresponding in number and arrangement with the said transfer rolls but more closely spaced, the
20 upper roll of each of the said pairs being movable with respect to the lower roll.
7. In apparatus of the character described,
- a work support, a rack support, a frame, a rack mounted in said frame and adapted to hold a plurality of rolls of transfer ma- 25 terial, said rack being arranged for movement in said frame whereby said rolls may be selectively moved into operative relation with respect to said work support, and means for effecting a transfer from a selected roll to work placed upon said support. 30
8. In combination, a work table, a work support slidably mounted on said table, a heated stamping head mounted to move vertically with respect to said table, means 35 adapted to actuate said stamping head, a guide roller connected to said table and adapted to guide a tape to and above said movable support, and a support adapted to movably hold a plurality of rolls of tape. 40

In witness whereof I hereto affix my signature.

OTTO P. WERNER.
